UNITED STATES PATENT OFFICE.

PALMER C. GOBLE, OF WAUKEGAN, ILLINOIS, ASSIGNOR TO CHICAGO HARDWARE FOUNDRY COMPANY, OF NORTH CHICAGO, ILLINOIS, A CORPORATION OF ILLINOIS.

DESIGN FOR A STOOL OR THE LIKE.

Application filed January 7, 1929. Serial No. 29,522. Term of patent 3½ years.

To all whom it may concern:

Be it known that I, PALMER C. GOBLE, a citizen of the United States of America, residing at Waukegan, in the county of Lake and State of Illinois, have invented a new, original, and ornamental Design for a Stool or the Like, of which the following is a specification, reference being had to the accompanying drawing, forming a part thereof.

The figure is a perspective view of a stool, showing my new design.

I claim:

The ornamental design for a stool or the like as shown.

PALMER C. GOBLE.
